MOUNTING FOR HIGH PRESSURE DIS-
CHARGE LAMPS

John Wesley Marden, East Orange, N. J., assignor,
by mesne assignments, to Westinghouse Electric
and Manufacturing Company, East Pittsburgh,
Pa., a corporation of Pennsylvania

Application April 22, 1936, Serial No. 75,723

7 Claims. (Cl. 176—122)

My present invention relates to electric vapor discharge lamps and particularly to such lamps employing a metal vapor, such as mercury, at a substantial pressure ranging from several millimeters to several atmospheres.

Lamps of this type are well known in the art and as is the customary practice the lamp itself or the envelope containing the electrodes between which the discharge occurs is surrounded by an outer vitreous envelope for the conservation of heat. Heretofore the inner envelope has usually been supported entirely within the outer envelope by the leading-in conductors which are connected to the electrodes and also form a seal with the inner envelope. Such suspension of the inner envelope renders the entire lamp of an exceptionally fragile nature as vibration in conjunction with temperature changes is apt to sever the connections of the leading-in conductors or 20 destroy the seal of the latter with the envelope thus rendering the lamp useless.

It is accordingly an object of my present invention to provide an electric vapor discharge lamp of rugged construction wherein the inner envelope is so supported as to relieve the leading-in conductors of strain.

Another object of my present invention is the provision of an electric vapor discharge lamp of economical construction wherein the inner envelope is supported by tubular sleeves which engage portions of the envelope so as to eliminate strain upon the leading-in conductors.

Still further objects of my present invention will become obvious to those skilled in the art by reference to the accompanying drawing wherein,

Figure 1 is an elevational view partly in cross section of a lamp constructed in accordance with my present invention.

Fig. 2 is a cross sectional view taken on the line II—II of Fig. 1.

Fig. 3 is a cross sectional view taken on the line III—III of Fig. 1.

Fig. 4 is a modified form of the lamp which my present invention may take, and

Fig. 5 is a fragmentary view in perspective and on an enlarged scale of the tube support of my present invention.

Referring now to the drawing in detail I have shown in Fig. 1 an electric vapor discharge lamp comprising an inner envelope 5 of a suitable vitreous material, such as hard glass, quartz, pyrex, or the like, and surrounded by an outer envelope 6, which may be of ordinary glass as is common in the art, with the space between the inner and 55 outer envelope either evacuated, filled with an

inert gas or filled with air. The outer envelope 6 is provided with a screw base 7, of the usual commercial type, suitably cemented thereto. Secured to the shell portion of this base 7 is a conducting and supporting rod 8 of substantially U-shaped configuration conforming substantially to the contour of the outer envelope 6 and extending interiorly thereof adjacent to the walls.

A similar conducting and supporting rod 9 extends from the center contact point of the base 10 7 co-axially with the longitudinal axis of the lamp and at its upper extremity is bent transversely of this axis. The inner envelope 6 is provided with suitable electrodes 10 and 12 to which are connected leading-in conductors 13 and 14 sealed to 15 tubular portions 15 of the inner envelope and extending exteriorly thereof.

The leading-in conductor 13 sealed to the upper tubular portion 15 of the inner envelope is suitably connected as by welding to the U-shaped 20 conducting and supporting rod 8 at a point coinciding with the longitudinal axis of the lamp and similarly the leading-in conductor 14 is secured, such as by welding, to the transversely extending portion of the conducting and supporting rod 9. 25

A suitable metallic conductor 16 is spirally wound about the envelope 5 and is connected to the conducting and supporting rod 8 adjacent the electrode 12 for the purpose of facilitating starting of the discharge within the inner envelope 5. 30

The construction of my lamp thus far described does not differ materially from the prior art. However, in the absence of my present invention the inner envelope 5 would be entirely supported by the leading-in conductors 13 and 35 14 due to its being suspended between the conducting and supporting rods 8 at the upper portion thereof and the extremity of the remaining conducting and supporting rod 9. In order, however, to relieve the leading-in conductors 13 and 40 14 from strain, which would otherwise render the same susceptible to disruption due to vibration or temperature changes, or the seal of these leading-in conductors with the tubular portions 15 45 of the envelope 5 to become destroyed, I support the inner envelope 5 by a sleeve member 17. This sleeve member 17 is formed of any suitable material, such for example as nickel or other metal, or the same may be made of insulating material. 50 These tubular sleeves engage the tubular portions 15 of the inner envelope 5 and at one end are provided with a flat extension bent at right angles to the longitudinal axis of the sleeve with the extremities of this flat portion being suitably 55

connected to the respective conducting and supporting rods 8 and 9.

Thus the upper tubular sleeve 17, as shown in Fig. 1, snugly fits the upper tubular portion 15 of the envelope 5 and is welded or otherwise affixed to the conducting and supporting rod 8 at a point adjacent to the connection of the leading-in conductor 13 therewith.

Likewise the lower tubular sleeve 17 snugly fits the lower tubular portion 15 of the envelope 5 and is similarly joined as by welding to the transversely extending portion of the conducting and insulating rod 9 adjacent the point of connection of the leading-in conductor 14 therewith.

During operation of the tube the inner envelope 5, as is well known, is subjected to considerably high temperatures, naturally resulting in contraction and expansion of the vitreous envelope. In order to compensate for such contraction and expansion without subjecting the tubular portions 15 of the inner envelope 5 to the possibilities of breakage due to the surrounding tubular sleeve 17, the latter is formed as a split cylinder with a portion overlapping, as can be more readily seen in Figs. 1 and 2. This accordingly enables the tubular sleeve 17, while maintaining firm engagement with the tubular portions 15 of the envelope 5 to likewise contract and expand due to temperature changes, while at the same time forming a rugged support for the envelope 5, which under all conditions relieves the respective leading-in conductors 13 and 14 from strain.

It thus becomes obvious to those skilled in the art that I have provided an electric vapor discharge lamp wherein the inner envelope is supported within an outer vitreous envelope in such manner as to form an economical and exceedingly rugged construction.

Moreover, the inner envelope to which the leading-in conductors for the electrodes are sealed is supported by a tubular sleeve firmly engaging portions of the envelope, which relieves the leading-in conductors from all strain thus obviating the possibilities of vibration destroying the connection of the leading-in conductors or the seal thereof with the envelope.

Although I have shown and described one specific embodiment of my invention I do not desire to be limited thereto as various other modifications of the same may be made without departing from the spirit and scope of the appended claims.

What is claimed is:

1. An electric vapor discharge lamp comprising a sealed envelope of vitreous material containing a vaporizable medium, electrodes disposed within said envelope, means for supplying electrical energy to said electrodes to cause a discharge therebetween including leading-in conductors connected to said electrodes and sealed into said vitreous envelope, and means surrounding said envelope provided with an angularly disposed portion positioned on the longitudinal axis of said envelope and connected to said leading-in conductor, and said means extending a substantial distance longitudinally thereof in engagement with the outer surface of said envelope adjacent the point of seal of said leading-in conductors therewith for supporting said lamp in order to eliminate strain on said leading-in conductors.

2. An electric vapor discharge lamp comprising a sealed envelope of vitreous material containing a vaporizable medium, electrodes disposed within

said envelope, means for supplying electrical energy to said electrodes to cause a discharge therebetween including leading-in conductors connected to said electrodes and sealed into said vitreous envelope, and means surrounding a portion of said envelope provided with an angularly disposed portion positioned on the longitudinal axis of said envelope and connected to said leading-in conductor, and said means extending a substantial distance longitudinally thereof in engagement with the outer surface of said envelope adjacent the point of seal of at least one of said leading-in conductors therewith for supporting said lamp in order to eliminate strain on the leading-in conductor adjacent said means.

3. An electric vapor discharge lamp comprising a sealed envelope of vitreous material containing a vaporizable medium and provided with tubular extensions, electrodes disposed within said envelope, means for supplying electrical energy to said electrodes to cause a discharge therebetween including leading-in conductors connected to said electrodes and sealed into said vitreous envelope, and means surrounding the tubular extensions of said envelope and in engagement therewith and mechanically connected to said leading-in conductors for supporting said lamp in order to eliminate strain on said leading-in conductors.

4. An electric vapor discharge lamp comprising a sealed envelope of vitreous material containing a vaporizable medium and provided with tubular extensions, electrodes disposed within said envelope between which a discharge occurs upon being supplied with electrical energy from a suitable source, leading-in conductors connected to said electrodes and sealed into said vitreous envelope, an outer vitreous envelope surrounding said sealed envelope provided with a base and having conducting and supporting rods extending from said base and connected to said leading-in conductors, and means connected to said conducting and supporting rods and engaging the tubular extensions of said sealed envelope for supporting the latter in order to eliminate strain on said leading-in conductors.

5. An electric vapor discharge lamp comprising a sealed envelope of vitreous material containing a vaporizable medium and provided with tubular extensions, electrodes disposed within said envelope between which a discharge occurs upon being supplied with electrical energy from a suitable source, leading-in conductors connected to said electrodes and sealed into said vitreous envelope, an outer vitreous envelope surrounding said sealed envelope provided with a base and having conducting and supporting rods extending from said base and connected to said leading-in conductors, and cylindrical members connected to said conducting and supporting rods and engaging the tubular extensions of said sealed envelope for supporting the latter in order to eliminate strain on said leading-in conductors.

6. An electric vapor discharge lamp comprising a sealed envelope of vitreous material containing a vaporizable medium and provided with tubular extensions, electrodes disposed within said envelope between which a discharge occurs upon being supplied with electrical energy from a suitable source, leading-in conductors connected to said electrodes and sealed into said vitreous envelope, an outer vitreous envelope surrounding said sealed envelope provided with a base and having conducting and supporting rods extending from said base and connected to said lead-

ing-in conductors, and metallic sleeves connected to said conducting and supporting rods and engaging the tubular extensions of said sealed envelope for supporting the latter to relieve said leading-in conductors from strain.

5 7. An electric vapor discharge lamp comprising a sealed envelope of vitreous material containing a vaporizable medium and provided with tubular extensions, electrodes disposed within said envelope between which a discharge occurs upon being supplied with electrical energy from a suitable source, leading-in conductors connected to said electrodes and sealed into said vitreous

envelope, an outer vitreous envelope surrounding said sealed envelope provided with a base and having conducting and supporting rods extending from said base and connected to said leading-in conductors, and a split sleeve member connected to said conducting and supporting rods and engaging the tubular extensions of said sealed envelope for supporting the latter to relieve said leading-in conductors from strain and to enable expansion and contraction of said split sleeve member with said sealed envelope.
